(57) **CLAIM**

What is claimed is the ornamental design for a snorkel, as shown.

DESCRIPTION

FIG. 1 is a right side, rear perspective view of the snorkel; FIG. 2 is a right side, front perspective view thereof; FIG. 3 is a left side, front perspective view thereof; FIG. 4 is a left side view thereof; FIG. 5 is a right side view thereof; FIG. 6 is a top view thereof; FIG. 7 is a bottom view thereof; FIG. 8 is a back view thereof; and, FIG. 9 is a front view thereof.

The broken lines showing of the snorkel are for the purpose of illustrating the trapezoid-like features and form no part of the claimed design.
